UNITED STATES PATENT OFFICE.

WILMUTH E. BLACKBURN, OF SUMMIT, NEW JERSEY.

GAME APPARATUS.

Application filed July 10, 1918. Serial No. 244,258.

To all whom it may concern:

Be it known that I, WILMUTH E. BLACKBURN, a citizen of the United States, and resident of Summit, in the county of Union 5 and State of New Jersey, have invented certain new and useful Improvements in Game Apparatus, of which the following is a specification.

This invention relates to improvements in 10 game apparatus, pertaining more particularly to means for controlling the activity of apparatus of this type.

Game apparatus of various types is well known, including apparatus in which there 15 is more or less requirement of skill in operation. Fees are generally charged for the use of the apparatus, and in some of the types—those in which the playing elements are fixed or otherwise secured in position, it 20 has been possible to provide for prepayment as a requisite for the use of the apparatus. Where, however, the apparatus includes playing elements which are entirely separate from the fixed elements, this prepayment 25 becomes more or less difficult, and it is the general practice to employ an attendant for the purpose of taking care of the playing elements and collect the fees, thus materially increasing the cost of operation 30 through the cost of additional labor.

The present invention is designed to overcome this difficulty and permit operation of this latter type of apparatus under prepayment principles, and at the same time provide 35 the apparatus in such form as to practically dispense with attendance. This is obtained generally by automatically collecting the balls or missiles at a point normally inaccessible, the allotted number of balls or 40 missiles being rendered accessible by manipulation of a control device in the presence of the fee token; the control device may be an element operative in the re-setting of the game apparatus.

Other objects are the provision of a mechanism which is simple and efficient in operation, durable in construction, and which is of low cost of manufacture.

To these and other ends, the nature of 50 which will be readily understood as the invention is hereinafter disclosed, said invention consists in the improved construction and combination of parts hereinafter fully described, illustrated in the accompanying 55 drawings, and more particularly pointed out in the appended claims.

In the accompanying drawings, in which similar reference characters indicate similar parts in each of the views—

Figure 1 is a perspective view showing 60 one form of game apparatus, with which my present invention is adapted for use; Figure 2 is a view, partly in section and partly in elevation, showing mechanism for carrying out the principles of the invention; Figure 65 3 is a horizontal sectional view of parts shown in Figure 2; Figure 4 is a cross-sectional view taken on line 4—4 of Figure 3; Figure 5 is a detail perspective view of a locking dog or pawl; Figure 6 is a detail 70 perspective view showing a simple form of actuating device operative in connection with the control.

The game apparatus illustrated is of the general type disclosed in my companion application filed August 21, 1917, Serial No. 187,327, in which *a* indicates a target carrying a plurality of goals or pockets *b*, the target being located at the rear of a runway *c* over which the balls or missiles are moved, 80 said runway having its rear end upturned—curved or inclined—as at *c'*, causing the travelling ball or missile to be trajectory upward from the runway into contact with a baffle *d* located above the goals, the latter deflecting 85 the ball or missile in the direction of the goals. The goals may have different goal values, and are preferably arranged in such manner that each discharges a ball or missile in such manner as to cause the latter to pass 90 into a ball race *e* located at one side of the runway, the balls being collected in the race *e*.

In a companion application I have disclosed an indicating mechanism which may 95 be utilized in connection with the apparatus, the exposure opening thereof being shown at *f* in Figure 1; an indicator element *g* being shown as exposing indications through the opening. The mechanism is of a type 100 requiring re-setting in advance of playing a game, and this re-setting lever is utilized in connection with the present invention, although it will be understood that the present invention may be utilized without the 105 indicating mechanism referred to. In the drawings I have indicated the lever at *h*, and the connection with the specific indicating structure at *h'*.

In practicing the present invention with 110 the game apparatus disclosed, I preferably foreshorten the race *e* so that its outer end

terminates a suitable distance from the playing end of the runway, the race preferably extending to a lower plane than the runway to permit the formation of a pocket 5 10 beneath the latter. This pocket may be of suitable formation, the drawing indicating it as having a curved wall 10^a which leads from the end of the fixed race *e* to the opposite side of the runway frame, 10 the outer end of the pocket being shown as partially open—sufficient space being provided to permit of the removal of balls or missiles therefrom when the latter have been permitted to enter the pocket and pass 15 into juxtaposition to a retaining member 10^b at the open end of the pocket.

Race *e* is shown as terminating at the entrance to the pocket, the race being continued in the form of a pivoted section or 20 support 11 which normally forms a continuation of the race so that the balls or missiles are free to travel on to such pivoted support in returning over the race, the latter being preferably sufficiently sloped to cause such movement of the balls or missiles as is usual. While support 11 is shown as equal in length 25 to the depth of the pocket, it will be understood that this is not arbitrary, since race *e* may extend beyond the wall 10^a of the pocket, in which case it is preferred that the bottom of the race be inclined transversely 30 similar to support 11. As support 11 is designed to deliver but a predetermined number of balls or missiles, it will be understood 35 that this may be controlled by increasing the length of race *e* or placing a filling block at the outer end of the support, where a less number of balls or missiles are to be delivered, the drawings indicating a number 40 which just fills the length of the support.

As shown in Figure 4, support 11 is normally inclined downwardly from its hinge line on a cross-section of the support, thus 45 normally retaining the balls or missiles in position thereon, the opposite edge of the support being connected to a link 12 carried by an arm 13 projecting from lever *h*, the latter being pivoted as at *h*², a stop 13' being provided to limit the travel of the lever 50 in one direction. As will be understood, the balls or missiles will remain in the position of figure 4 as long as lever *h* is not shifted, thus retaining the supply for playing the game inaccessible. If, however, lever *h* be 55 moved toward the left in Figure 2, the movement will raise the free edge of the support and place the latter on an inclination above the horizontal, with the result that the balls or missiles contained thereon will roll off the 60 support and pass into the pocket where they will pass to the open end of the latter. As this upward movement of the support carries the latter above the plane of the bottom of race *e* it will be understood that any 65 balls or missiles which may have been held

in the race will be prevented from advancing until the support again returns to its normal position, so that any desired excess of balls or missiles may be contained in the race without affecting the delivery of a pre-determined number to the pocket. 70

As heretofore pointed out, one of the features of the present invention is to provide for prepayment, and this is had by preventing the pivotal movement of lever *h* excepting when the fee token has been placed in the apparatus, this token controlling the ability to shift the lever. The mechanism for providing this result is more particularly 75 illustrated in Figures 2, 5 and 6. 80

As shown in Figures 2 and 6, lever *h* is provided with a control device in the form of a token seat 14 normally located in vertical alignment with a slot 15 in the frame of the runway, this seat being formed as a part 85 of a plate or member 16 carried by the lever. Said seat is so arranged that when the lever is in normal position the token will remain seated thereon, but when the lever is shifted the token will pass therefrom into a runway 90 17 which may be carried by the lever and leading to a suitable accumulating receptacle, not shown.

18 indicates a latching dog or pawl, shown 95 as of the gravity type and pivotally mounted as at 18^a. This dog or pawl carries a projection 18^b which normally lies within a recess 16^a of member 16, the end of the dog or pawl extending into a depression or recess 16^b. Dog or pawl 18 is also formed with an 100 opening 18^c extending in alignment with the slot 15 and through which the token passes en route to its seat. As shown, opening 18^c is flared at its lower end to provide a wall 18^d. 105

As will be seen from Figure 2, when the token is in position on its seat, movement of the lever toward the left will cause the edge of the token to contact with wall 18^d, with the result that as the lever continues its 110 movement, dog 18 will be raised sufficiently to carry the end of the dog above the top of depression 16^b, permitting the lever to continue its movement, projection 18^b raising the dog sufficiently to free the token 115 from any retaining effect which may be provided by the dog, so that the token is free to pass on into the runway 17. This movement of the lever delivers the balls or missiles, as heretofore explained. When the 120 lever is freed, it may be returned to normal position in any desired manner, as by a spring *h*³.

When, however, attempt is made to shift the lever in the absence of a token, the end 125 of dog or pawl 18 will contact with a wall of depression 16^b, thus preventing further movement of the lever and consequently retaining support 11 in position to prevent delivery of the balls or missiles thereon. 130

As will be clear from the above, no special attendance is required in connection with the apparatus. As each ball is played, it returns to the race *e* and the total balls are 5 collected therein and on the support 11 inaccessible for further playing until lever *h* has been actuated to deliver a new supply for the next player or game. As the movements of the lever are dependent on the 10 presence of the fee token, prepayment must be had to permit the playing to take place. Obviously, the mechanism employed is of simple character, efficient in operation, durable in construction, and capable of manufacture at low cost.

While I have herein shown and described a preferred embodiment of the invention and one form of game apparatus to which it may be applied, it will be readily understood 20 that this is more or less illustrative, the invention not being specifically limited to the particular form or arrangement of the mechanism or the particular surroundings in which it may be employed, since the exigencies of use may require changes or variations 25 therein or such changes or modifications may be found desirable for other reasons. I therefore desire to be understood that I reserve the right to make any and all 30 such changes or modifications of the invention as may be found desirable or essential in so far as the same may fall within the spirit or scope of the invention as expressed in the accompanying claims, when broadly 35 construed.

Having thus described my invention, what I claim as new is—

1. In apparatus of the character described and in combination, a shiftable support, a 40 pivoted lever operative to position and shift the support, said lever being normally inclined from the vertical and movable toward and from the vertical in the support shifting movements, said lever having a seat 45 for a token with the seat operative to support the token thereon when the lever is in its normal position and to permit movement of the token from the seat when the lever is moved to the vertical position, and means 50 for normally maintaining said lever against

movement to prevent support shifting action, said means including a latch element normally cooperating with the lever to lock the latter against such movement, said element being shiftable to release the lever in 55 the presence of a token, said latch element being located in the path of travel of the token and slotted for the passage of the token and positioned to direct the token to such seat when the lever is in its held position.

2. In apparatus of the character described and in combination, a shiftable support, a pivoted lever operative to position and shift the support, said lever being movable between vertical and inclined positions during the support shifting movements and having a token seat, said seat having a configuration to retain the token in position when the lever is in an inclined position and ineffective 70 to provide such support when the lever is moved to the vertical position, a latch device cooperative with the lever to normally maintain the lever locked, said device being relatively positioned to cause movement of 75 the device from latching position during lever movement had in the presence of a token on said seat, said latch element being located in the path of travel of the token and slotted for the passage of the token and 80 positioned to direct the token to such seat when the lever is in its held position.

3. In apparatus of the character described and in combination, a shiftable support, a pivoted lever operative to position and shift 85 the support, said lever having a token seat, a pivoted latch element normally cooperative with the lever to maintain the latter locked, said element having a face opposing said seat and normally positioned in the path of 90 travel of a token carried on said seat to provide movement of the element to release the lever by such token movements, and a chute carried by and movable with the lever to receive the token when the lever is moved to a 95 predetermined position.

Signed at New York, in the county of New York and State of New York, this fifth day of July, A. D. 1918.

WILMUTH E. BLACKBURN.
